F. S. CARR.
TURN BUTTON FASTENER.
APPLICATION FILED OCT. 5, 1918.

1,303,770.

Patented May 13, 1919.

UNITED STATES PATENT OFFICE.

FRED SUMNER CARR, OF CAMBRIDGE, MASSACHUSETTS, ASSIGNOR TO CARR FASTENER COMPANY, OF CAMBRIDGE, MASSACHUSETTS, A CORPORATION OF MAINE.

TURN-BUTTON FASTENER.

1,303,770.

Specification of Letters Patent.

Patented May 13, 1919.

Application filed October 5, 1918. Serial No. 257,049.

To all whom it may concern:

Be it known that I, FRED SUMNER CARR, a citizen of the United States, residing at Cambridge, in the county of Middlesex and

5 State of Massachusetts, have invented new and useful Improvements in Turn-Button Fasteners, of which the following is a specification.

This invention relates generally to a fastener for carriage curtains and the like, comprising a shank adapted to be attached to a support such as the body of a vehicle or a member of the frame of a vehicle top, and formed to enter a buttonhole or eyelet in a 10 curtain or cover portion, and an oblong button pivoted to the shank and formed to register with and freely enter a buttonhole when turned to one position, and to be turned crosswise of the buttonhole to overhang portions of the margin thereof and confine the curtain or cover portion against removal from the shank. The shank is usually of oblong form corresponding to that of the buttonhole and button.

25 In Letters Patent No. 1,253,350, dated January 15, 1918, I show a type of turn button fastener in which the shank and its attaching base are made in a single sheet metal piece or part, and are adapted to coöperate 30 in yieldingly confining the button in either of the described positions, without the employment of retaining devices supplemental to the shank and formed separately therefrom.

35 The present invention consists in certain improvements on the said patented fastener which I will now proceed to describe and claim.

The invention has for its chief object to 40 enable the button to be yieldingly confined in either of the described positions without the employment of retaining devices or registering means supplemental to the shank and button and formed separately therefrom, 45 the invention, in its preferred form, being embodied in only two parts or pieces which include as integral parts thereof the registering means for yieldingly confining the button in its different positions.

50 The invention is embodied in the improvements which I will now proceed to describe and claim.

Of the accompanying drawings, forming a part of this specification:

55 Figure 1 shows in perspective the parts of

a turn-button fastener embodying the invention, said parts being separated.

Fig. 2 shows in section the parts shown by Fig. 1 when assembled.

Fig. 3 is a section on the plane of line 3—3, 60 Fig. 2, and a plan view of parts below said line.

Fig. 4 is a view similar to Fig. 3, showing a different adjustment.

Figs. 5 and 6 are fragmentary sectional 65 views illustrating a different construction of the button stud hereinafter described.

Fig. 7 is a fragmentary perspective view illustrating the stud shown by Fig. 5.

Fig. 8 is a view similar to Fig. 6, showing 70 a different arrangement of the bearing flanges hereinafter described and a spring washer.

Fig. 9 is a view similar to Fig. 8, the washer being omitted.

The same reference characters indicate the same parts in all of the figures.

In the drawings, 16 represents the shank and 17 the button of a turn-button fastener. The shank is a hollow post, formed from 80 sheet metal by suitable dies and of oblong form in cross section, the shank being provided at its inner end with an attaching base 18, adapted to be secured to a support.

The head of the shank is divided by slots 85 19 into sections, said slots being preferably extended through the upstanding wall of the shank, as indicated at 19^a, Fig. 1. The head therefore includes two separable sections, which are yieldingly pressed together by the 90 resilience of the base 18, which continuously surrounds the shank.

The meeting edges of the head sections are provided with coinciding recesses 20, forming an expandible angular bearing, which is extended or widened by flanges 20^b integral with the head sections.

The button 17 is provided with an angular stud 21, journaled in said bearing, the form of the bearing and stud being such that, 100 when the stud is turned, it alternately expands the bearing, as indicated by Fig. 4, and permits the bearing to close, as shown by Fig. 3. When the bearing is closed, it is adapted to yieldingly confine the stud and 105 button in different angular positions.

As here shown, the bearing and stud are of polygonal form, the stud being preferably rectangular, with slightly rounded corners, and the bearing being preferably provided 110

with faces 20^a, which are obliquely arranged to prevent the corners of the shank from binding inoperatively when the shank is turned from the position shown by Fig. 3 to 5 that shown by Fig. 4.

The structure thus far described is substantially the same as that disclosed by the above-mentioned patent. In accordance with the present invention, I provide the means 10 next described for confining the stud 21 against endwise movement in the bearing and withdrawal therefrom. As shown by Figs. 1 and 2, the button and shank are hollow, and formed from sheet metal, the shank 15 being provided with a reduced extension 21^a of lesser thickness than the body of the stud and adapted to be upset, as shown by Fig. 2, and thus form a bur on the inner end of the stud. A washer 23 is applied to the extension 20^a, before the latter is upset, said washer being engaged with the bur, and constituting a wear-sustaining stud-enlargement and contacting with the portions of the stud head formed by the inner ends of the 25 flanges 20^b.

As shown by Figs. 5, 6 and 7, the stud and button may be solid, the inner end of the stud being preferably cylindrical and provided with a recess 24, the margin of which 30 is adapted to be upset to form a bur 24^a, as shown by Fig. 6. A washer 27 is applied to the stud before its outer end is upset, as indicated by dotted lines in Fig. 5, and secured by the bur, as shown by Fig. 6.

35 When the button and its shank are constructed of sheet metal, they may be made from a sheet metal blank having a seamless central portion forming the bottom of the button and the shank 21, and wings forming 40 the sides and top of the button, said wings meeting to form a joint or seam 14^a, as shown by Figs. 1 and 2.

The bearing flanges may project upwardly from the sections of the shank head, as shown 45 by Figs. 8 and 9, where said flanges are designated 20^c, the bottom of the button having a recess 30 receiving the flanges. The flanges 20^c projecting outwardly may be more conveniently formed integral with the stud 50 head than the inwardly projecting flanges 20^b. Moreover, when the said flanges project outwardly, the inner sides of the head sections present flat faces forming extended bearings for the shank enlargement, whether 55 said enlargement be the washer 27, or the bur 24^a shown by Fig. 9, the washer being omitted. The washer may be curved and resilient, as shown by Fig. 8, to exert a downward yielding pressure on the shank and button, preventing the button from rattling.

The washer 27 constitutes a wear-sustaining stud-enlargement confining the stud in the bearing and having a diameter greater than that of the bur, the diameter of the 65 washer being sufficient to compensate for the

separation of the head sections from each other by the stud when the latter is turned to the position shown by Fig. 4, so that the operative bearing of the stud-enlargement on the head sections is not affected by the expansion of the head. The diameter of the bur 24^a is necessarily limited. Moreover, said bur, especially in the sheet metal form shown by Figs. 1 and 2, is liable to be cracked at intervals when it is being formed, so that it 75 is not continuous. This is an objection which I overcome by the employment of a wear-sustaining washer supplementing the bur.

I claim:

1. A turn-button fastener comprising a 80 shank having an attaching base, a head divided into separable sections which are yieldingly pressed toward each other, the opposed edges of said sections having coinciding recesses forming an expansible bearing, a button having a stud journaled in said bearing, and yieldingly confined thereby in different angular positions, the inner end of the stud being upset to form a bur, and a washer engaged with said bur and constituting a continuous annular wear-sustaining stud-enlargement confining the stud in the bearing, said washer having a diameter greater than that of the bur, and sufficient to compensate for the separation of the head sections from 95 each other by the stud.

2. A turn-button fastener comprising a shank having an attaching base, a head divided into separable sections which are yieldingly pressed toward each other, the opposed edges of said sections having coinciding recesses forming an expansible bearing, a button having a stud journaled in said bearing, and yieldingly confined thereby in different angular positions, the inner end of the stud being upset to form a bur, and a washer engaged with said bur and constituting a wear-sustaining stud-enlargement bearing on portions of said head and confining the stud in the bearing, said washer being curved and 100 resilient to prevent rattle of the button.

3. A turn-button fastener comprising a shank having an attaching base, a head divided into separable sections which are yieldingly pressed toward each other, the opposed edges of said sections having coinciding recesses, and outwardly projecting flanges coinciding with said recesses and forming an expansible bearing located above the head, the inner sides of the head sections forming flat faces below the bearing, a button having a stud journaled in said bearing and yieldingly confined thereby in different angular positions, the inner end of the button being recessed to receive said flanges, and the inner end of the stud being upset to form a bur, and a washer engaged with said bur and constituting a wear-sustaining stud enlargement bearing on said flat faces and confining the stud in the bearing.

4. A turn-button fastener comprising a shank having an attaching base, a head divided into separable sections which are yieldingly pressed toward each other, the opposed edges of said sections having coinciding recesses, and outwardly projecting flanges coinciding with said recesses and forming an expandible bearing located above the head, the inner sides of the head sections forming flat faces below the bearing, a button having a stud journaled in said bearing and yieldingly confined thereby in different angular positions, the inner end of the button being recessed to receive said flanges, and the inner end of the stud being upset to form a bur, and a washer engaged with said bur and constituting a wear-sustaining stud enlargement bearing on said flat faces and confining the stud in the bearing, said washer being curved and resilient to prevent rattle of the button.
5. A turn-button fastener comprising a shank having an attaching base, a head divided into separable sections which are yieldingly pressed toward each other, the opposed edges of said sections having coinciding recesses, and outwardly projecting flanges coinciding with said recesses and forming an expandible bearing located above the head, the inner sides of the head sections forming flat faces below the bearing, a button having a stud journaled in said bearing and yieldingly confined thereby in different angular positions, the inner end of the button being recessed to receive said flanges, and the inner end of the stud being provided with an enlargement bearing on said flat faces and confining the stud in the bearing.

In testimony whereof I have affixed my signature.

FRED SUMNER CARR.
